(57) **CLAIM**

The ornamental design for a laser range finder, as shown and described.

DESCRIPTION

FIG. 1 is a front, top, and left side perspective view of a laser range finder showing my new design;

FIG. 2 is a rear, bottom, and right side perspective view thereof;

FIG. 3 is a front elevational view thereof, the rear view being a mirror image of FIG. 3;

FIG. 4 is a top plan view thereof;

FIG. 5 is a bottom plan view thereof;

FIG. 6 is an enlarged right side elevational view thereof; and,

FIG. 7 is an enlarged left side elevational view thereof. The features shown in broken lines in the drawings depict environmental subject matter only and form no part of the claimed design. The dash-dotted lines denote the boundary of the claim and form no part of the claimed design.
